TEMPERATURE REGULATION FOR REFRIGERATORS

Saul C. Hoffberger, Baltimore, Md., assignor to
The Bohn Refrigerator Company, Baltimore,
Md., a corporation of Maryland

Application October 15, 1937, Serial No. 169,313

17 Claims. (Cl. 62—31)

This invention relates to refrigeration, and more particularly to refrigerators utilizing solid refrigerants, in which means are provided for maintaining relatively constant temperatures within said refrigerator with wide variation of refrigerant, and more particularly to such methods and means of refrigeration in which the temperature maintained in the refrigerator may be regulated, but is maintained substantially constant for any set of given conditions.

For a number of years mechanical refrigeration offered many advantages which led to displacement of refrigerators employing solid refrigerants. There are, however, various advantages which refrigerators employing solid refrigerants have.

In more recent years refrigeration by means of solid refrigerants has been materially improved leading to refrigerators in which the temperature was maintained relatively constant even though the content of refrigerant in the ice compartment might vary over wide limits, and in fact even when the amount of refrigerant was only 10% of the capacity of the ice compartment, nevertheless substantially constant temperatures were maintained. However, in such refrigerators no means were provided enabling ready and simple variation of the degree of refrigeration or the temperature maintained to be controlled.

Among the objects of the present invention is the production of refrigerators utilizing solid refrigerants in which means are provided for regulating the temperature maintained, and means are utilized which enable variation in temperature to be obtained, while yet maintaining substantially constant temperatures for any given set of conditions.

Other and further objects and advantages will appear from the more detailed description set forth below, it being understood, however, that this more detailed description is given by way of illustration and explanation only and not by way of limitation, since various changes therein may be made by those skilled in the art without departing from the scope and spirit of the present invention.

In connection with that more detailed description, there is shown in the accompanying drawings, in

Figure 1, a fragmentary transverse section through a refrigerator produced in accordance with the present invention, and showing the means for varying the temperature while main-

taining substantially constant temperature for any set of conditions; in

Figure 2, a fragmentary sectional view of the refrigerator of Figure 1, some parts being broken away to show structural features; in

Figure 3, a section taken on the line 3—3 of Figure 2; in

Figure 4, a fragmentary transverse sectional view of a modified form of control element shown in position in a refrigerator; in

Figure 5, a fragmentary sectional view of the structure shown in Figure 4 with parts broken away; in

Figure 6, a section taken on the line 6—6 of Figure 5; in

Figure 7, a fragmentary transverse sectional view of a further modification; in

Figure 8, a fragmentary sectional view of the structure shown in Figure 7 with parts broken away to show structural features; in

Figure 9, a section taken on the line 9—9 of Figure 8; in

Figure 10, a fragmentary transverse section through a modified form of temperature control element shown in position in a refrigerator; and in

Figure 11, a fragmentary sectional view of the structure of Figure 10, some parts being broken away to show structural features.

As shown in the devices of the drawings, the present invention is particularly concerned with control of temperature and temperature regulation in refrigerators, particularly of the type utilizing solid refrigerants, such as ice, solid carbon dioxide, etc. Such refrigerators comprise

the usual refrigerator structure indicated by the walls R providing compartments, such as the ice compartment I and the food compartment F. These compartments are formed in the refrigerator by a floor member M, usually of metal or

of material having a heat conductivity similar to that of metal, whereby air from the food compartment F contacts with the metallic floor member M and is refrigerated. Two types of refrigerators of this character may be noted: those in

which air circulates from the food compartment into and through the ice compartment, and those in which the food compartment and ice compartment are substantially sealed from one another, so that air from the food compartment, although impinging against the metallic floor

member or face of the ice compartment, is cooled without circulating through the ice compartment. The present invention may be utilized with either type of structure, but more desirably is

5

concerned with refrigerators in which there is no substantial circulation of air from the food compartment, since in such structures more efficient control of temperature regulation is provided with minimum consumption of ice for maintenance of desired temperature. Consequently in such cases, the floor member M is mounted on a shoulder S on the inner wall of the refrigerator, and is of such size as to seal the ice compartment against any substantial entry of air from the food compartment.

The floor member M also is desirably provided with radiation ribs T, usually in the form of substantially flat ribs angularly disposed with respect to the plane of the floor member or metallic face M, and extending over a substantial portion of the effective face of the floor member, such radiation ribs being of metal and increasing the surface providing for refrigeration of air circulating against such floor member. As noted above, structures of this character including floor members provided with radiation ribs may be utilized in refrigerators in which air may circulate from the food compartment into and through the ice compartment, but more desirably are employed in structures where no substantial entry of air from the food compartment into the ice compartment occurs, whereby more efficient control of temperature is secured.

Particularly in connection with the present invention it has been found that in structures of the character set forth above, the temperature maintained in the refrigerator, or more particularly in the food compartment, may be varied by the degree of circulation of air, or the extent to which air is permitted to contact with the metallic face or floor member, with or without radiating ribs. By varying the circulation of such air and the degree to which the air may contact such metallic face or floor member of the ice compartment, regulation of temperature in a refrigerator employing solid refrigerants may be obtained, although for any given set of conditions substantially uniform temperatures will be maintained. The present invention provides simple means and methods for accomplishing that result in this type of structure, and secures such results by the utilization of a circulation control element.

In the form of circulation control element shown in Figures 1 to 3, the drip pan 1 and baffle 2 are placed in the food compartment immediately adjacent the metallic face or floor member M, providing passages through which the air of the food compartment circulates in order to be cooled. The drip pan 1 may thus take the form of a structure having side walls 3, 4, separated by a floor element or drip pan 5 provided with a central opening 6, the floor member 5 having upturned edges 7 defining said opening 6, so that drip or condensate which collects on the floor member 5 is diverted to the drain pipe 8. The baffle or dome member 2 is carried on the side walls 3, 4 above the floor opening 6, and may desirably be V-shaped in character, so that drip or condensate collecting on the upper surface of the dome member 2 is diverted to the floor member 5. The baffle or dome member 2 is spaced above the floor member 5 to provide passages both above and below the dome member 2. The passages between the dome member 2 and the floor member 5 are adapted to be restricted or varied in size by means of gate or flap valves 9, 10 pivotally mounted at each end of the baffle or dome member 2. Each of the valves 9 and 10 is

provided with an operating knob 11, 12 extending forwardly of the food compartment, so that rotary movement of the knobs 11, 12 move the valves 9, 10 to close completely or to restrict partially the passages between the baffle or dome member 2 and the floor member 5 of the circulation control element. The circulation control element as a unit may be mounted on the walls R of the refrigerator, desirably in the food compartment immediately adjacent the metallic face 10 or floor member M.

In structures of this character with the valves 9 and 10 open, air circulates both above and below the baffle member 2, some of the air passing below the baffle member 2 and through the opening 6 in the drip pan or floor member 5 of the circulation control element. The degree of such circulation of air through these passages may be controlled by operation of the valves 9 and 10, and depending on the amount of the air that is permitted to circulate between the dome member 2 and the drip pan 5, the temperature in the food compartment is controlled and capable of variation within substantial limits, although for a particular position of the valves 9, 10 such temperature will be maintained substantially constant, even with wide variation in the amount of the refrigerant in the ice compartment I. Since the knobs 11, 12 are directly available for operation from the front of the food compartment, they may be set to determine the temperature to be maintained in the food compartment. If the valves 9, 10 are closed so that no air can circulate between the dome member 2 and the drip pan 5, all air circulation is necessarily against the metallic face or floor member M and any radiating ribs T provided thereon, whereby one set of temperature conditions is maintained substantially constant. By operating the valves 9 and 10 the passage of air is controlled, and the air circulating through such passages restricted according to the settings of the gate valves 9 and 10. Each position of the valves 9 and 10 will give a different temperature in the food compartment, but for any such position of the valves 9 and 10, the temperature will be maintained substantially constant. Such structure, therefore, readily enables variation in temperature as desired in the food compartment, although providing at the same time for substantially constant temperatures being maintained for any given set of conditions.

Any desired means may be provided for varying the passages and circulation of air in the food compartment. Thus in the structure shown in Figures 4 to 6, the two valves 9 and 10 may be simultaneously operated by a single operating element or knob 20. For this purpose, the knob 20 is directly attached to a strap 21 extending on each side of the knob 20 and provided with an opening at each end thereof in which a tie rod 22 is seated and serves to connect the strap 21 with a strap 23 attached to each of the valves 9 and 10. Operation of the knob 20 will simultaneously actuate the valves 9 and 10. Otherwise the structure and its operation is analogous to that described above for Figures 1-3.

Further structural modification is illustrated in Figures 7 to 9. In this structure the gate valves 38 and 39 are mounted for hinge movement on rods 40, 41 carried on the side walls 3, 4 of the circulation control element, the rods 40, 41 being spaced from each other, and the space between them being covered by the baffle or dome element 75

42. Each of the rods 40, 41 is provided with a gear 43, 44, which gears mesh so that movement of the gear 44 operates gear 43, and produces actuation of both valves 38 and 39. One of the rods 40, 41 is provided with an operating knob 45, so that actuation of the knob 45 results in movement of the gate valves 38, 39 to control the passages between the dome or baffle member 42 and the floor member or drip pan 5. The other structural details of the device as shown in Figures 7 to 9 and their operation and functions are otherwise substantially the same as that explained above in connection with Figures 1-3.

Further structural modification is illustrated in Figures 10 and 11. In the form of devices and structure shown in Figures 1-9 above, substantial circulation of air is permitted at all times, temperature control being maintained by diversion of such circulating air into a multiplicity of channels. In the structural modification shown in Figures 10 and 11, the arrangement is such that the circulation of air in contact with the floor member M can be so controlled that with one setting of the device, only a minimum amount of air is permitted to circulate, provision for some circulating air at all times, however, being offered, while with the maximum opening of the valves a maximum amount of circulation of air is permitted, intermediate settings of the valve permitting control of the circulation of air at intermediate values, thus providing for regulation of temperatures as desired, it still being kept in mind that for any given setting of valves, a substantially uniform temperature will be maintained in the food compartment of the refrigerator with minimum consumption of solid refrigerant for maintenance of refrigeration. In the structures of Figures 10 and 11, the floor member M provided with the radiation ribs T are employed, such floor member M resting on the shoulders S, S carried on the side walls of the refrigerator structure, the depth of the floor member M being substantially equal to the depth of the refrigerator, so that no substantial circulation of air from the food compartment F into the refrigerant compartment I is permitted. At the same time, the floor member M with attached radiation ribs T may be removed for cleaning or other purposes, as desired.

The drip pan is desirably formed as a double walled structure having upper and lower walls 51 and 52 respectively, so that the lower wall 52 can collect condensate that may form on the upper wall 51. The upper and lower walls 51 and 52 are provided with central openings 53 and 54 respectively, the edges of the openings 53 and 54 being upturned, as shown at 55 and 56, respectively, to form a lip so that condensate which collects on the walls 51 and 52 is conducted along the channels formed between the walls 51 and 52 and the upturned lip portions 55 and 56 to the drain pipe; there being an upper drain pipe 57 which conducts the condensate from the upper portion of the drip pan into the drain pipe 58, the latter also receiving the drip water collected by the lower wall 52. The drain pipe 57 may be rigidly attached to the rear central portion of the upper wall of the drip pan, while the drain pipe 58 is attached to the rear central portion of the lower wall of the drip pan.

The double walls 51 and 52 of the drip pan are joined together at their sides, as shown at 59, the front double walls of the drip pan being closely associated together and supported in position by the extension 60, while the rear walls

of the double walled drip pan are secured directly to the back wall of the refrigerator, as indicated at 61.

The baffle or dome member 62 is desirably composed of a front wall 63 and a rear wall 64, to which are attached side walls 65 and 66, and a top member 67. The top 67 extends forwardly of the front wall 63 to provide an extension 68 which rests on a projection 69 carried on the front wall of the drip pan structure; the space 10 formed between the front wall 63 of the dome member 62 and the front wall of the drip pan structure providing a passage in which the means for operating the gate valve to be described below, may be placed. The rear wall 64 of the dome 15 member 62 fits into guides 70 carried on the rear wall of the drip pan structure. Condensate or drip which collects on the upper surfaces of the side walls 65 and 66 of the dome member 62 collects in the channel formed by the upturned 20 lower edges 71 and 72 respectively, and is carried transversely over to the collecting channels on the upper drip pan wall 51 and from thence is carried into the drain pipes. The slanting side walls 65 and 66 provide a central opening 13 25 therebetween, which is positioned above the openings 53 and 54 of the double walled drip pan, the top 67 of the dome member being placed above this opening 13 and forming a dome thereover. Carried on the lower wall 52 of the double walled 30 drip pan, channel shaped drip collectors 74 and 75 may be provided, positioned just below the channel formed by the upturned edges 71 and 72 of the slanting walls 65 and 66 respectively of the dome member; such drip collectors 74 and 75 35 being carried on the lower wall 52 and carrying any drip or condensate back into the channel formed between the upturned edge 56 of the lower wall 52 of the drip pan structure, so that it may ultimately reach the drain pipe. 40

From a consideration of the structure so far described, it will be apparent that since the floor member M substantially closes the opening between the food compartment F and the refrigerant compartment I, any air circulating within 45 the food compartment F must pass along the spaces 16, 17, formed between the sides of the double walled drip pan, and the shoulders S, S circulating along the lower face of the floor member M and the radiating ribs T. It is apparent, 50 therefore, that with such structure the provision of gate valves at the extreme sides of the drip pan will enable the passages 16 and 17 to be controlled in order to determine the amount of circulation of air which may take place. For this 55 purpose, gate valves 78 and 79 are carried on rods 80 and 81 respectively, the latter being supported on the slanting portion of the upper wall 51 of the drip pan, as in lugs 82 and 83, such lugs or projections 82 and 83 having openings therein 60 to receive the rods 80 and 81 respectively, which can be rotated in such supporting lugs, rotation of the rods also rotating the gate valves 78 and 79 which are rigidly attached to the rods 80 and 81. The size of the valves 78 and 79 is substantially equal to the distance between the drip pan upper wall 51 at this point and the edge of the supporting shoulder S nearest thereto. For operation of the valves 78 and 79, a tie rod 84 is supplied for each valve 78 and 79, one end of the 65 tie rod 84 being attached to the valve 78 on the one hand, and the other tie rod 84 being attached to the valve 79, these tie rods 84 being attached at their inner ends to the strap 85 mounted on the pin 86 to which the knob 87 is attached, so 70 75

that operation of the knob in a clockwise manner simultaneously operates the valves 78 and 79 to open the circulating passage; while operation of the knob in counter-clockwise direction serves to 5 close the passages 76 and 77 against circulation of air, the length of the rods 84, however, being such that the passages 76 and 77 cannot be completely closed even at the full movement of the knob 87, leaving a small passage 88 and 89 at all 10 times through which some circulation—although a minimum—may take place. While the valves 78 and 79 may be independently operated by individual operating knobs, the structure as shown 15 is particularly useful for household and other purposes, enabling simultaneous setting of the valves to be produced. The front wall of the drip pan may carry a scale on which a range of temperatures, such as between 40 and 50° F. may be indicated, so that when the knob is turned to 20 such position on the indicating scale, temperatures of the indicated order will be substantially maintained in the refrigerator.

The operation and function of structures of the character illustrated in Figures 10 and 11 25 will be apparent from the description given above, particularly in view of the analogous operation of structures explained above as shown in Figures 1-9. Ready and substantial control of the temperatures to be maintained in the food compartment F is secured in this way in a relatively 30 simple and efficient structure.

It will thus be seen that in accordance with the present invention, simple methods and means are provided for variation in the temperature 35 to be maintained in the food compartment of a refrigerator utilizing solid refrigerants, such methods and means including control of the air circulating from the food compartment against the metallic face or floor member of the ice compartment. Various degrees of temperature may 40 be maintained in the food compartment depending on the opening or degree of opening for any given seating of the valves. Thus temperature control while maintaining constant temperature 45 for each control setting is secured.

Having thus set forth my invention, I claim:

1. A circulation control element for refrigerators comprising side walls spaced apart by a floor member having an opening therein, a dome member carried on said side walls above said 50 opening and spaced from said floor member cooperating therewith to provide passages between the dome and floor members, and means for restricting said passages to control the amount of 55 air that may circulate through said passages.

2. A circulation control element for refrigerators comprising side walls spaced apart by a floor member having an opening therein, a dome member carried on said side walls above said 60 opening and spaced from said floor member cooperating therewith to provide passages between the dome and floor members, and manually operable gates for controlling the amount of air that may circulate through said passages.

3. In a refrigerator having a food compartment and an ice compartment, the ice compartment having a metallic face against which air from the food compartment may circulate for refrigeration, a baffle adjacent the metallic face 65 of the ice compartment cooperating therewith to provide an air circulating passage between said baffle and said metallic face, an opening in said baffle for diversion of circulating air, and means for restricting said opening to control the air 70 passing therethrough.

4. In a refrigerator having a food compartment and an ice compartment substantially sealed against entry of air from said food compartment, the ice compartment having a metallic face against which air from the food compartment may circulate for refrigeration, a baffle adjacent the metallic face of the ice compartment cooperating therewith to provide an air circulating passage between said baffle and said metallic face, an opening in said baffle for diversion of circulating air, and means for restricting said opening to control the air passing therethrough. 75

5. In a refrigerator having a food compartment and an ice compartment substantially sealed against entry of air from said food compartment, the ice compartment having a metallic face against which air from the food compartment may circulate for refrigeration, a baffle within the food compartment adjacent the metallic face of the ice compartment cooperating therewith to provide an air circulating passage between said baffle and said metallic face, an opening in said baffle for diversion of the circulating air, and means for restricting said opening to control the air passing therethrough. 15

6. In a refrigerator having a food compartment and an ice compartment, the ice compartment having a metallic face provided with radiation ribs against which air from the food compartment may circulate for refrigeration, a baffle within the food compartment adjacent the metallic face of the ice compartment cooperating therewith to provide an air circulating passage between said baffle and said metallic face, an opening in said baffle for diversion of circulating 20 air, and means for restricting said opening to control the air passing therethrough. 25

7. In a refrigerator having a food compartment and an ice compartment, the ice compartment having a metallic face against which air from the food compartment may circulate for refrigeration, a circulation control element within the food compartment comprising side walls spaced apart by a floor member having an opening therein, a dome member carried on said side walls 40 above said opening and spaced from said floor member cooperating therewith to provide passages between the dome and floor members, and means for restricting said passages to control the amount of air that may circulate through 45 said passages. 50

8. In a refrigerator having a food compartment and an ice compartment, the ice compartment having a metallic face against which air from the food compartment may circulate for refrigeration, a refrigeration control element within said food compartment adjacent the metallic face of the ice compartment, said refrigeration control element comprising side walls spaced apart by a floor member having an opening 55 therein, and gate valves carried on said side walls adjacent said floor opening to close said opening against passage of substantial air therethrough. 60

9. In a refrigerator having a food compartment and an ice compartment, the ice compartment having a metallic face provided with radiation ribs against which air from the food compartment may circulate for refrigeration, a circulation control element mounted within the food compartment adjacent the metallic face of the ice compartment, said circulation control element comprising side walls spaced apart by a floor member having an opening therein, a dome member carried on said side walls above said opening and spaced from said floor member cooperating there- 70 75

with to provide passages between the dome and floor members, and means for restricting said passages to control the amount of air that may circulate through said passages.

5 10. The method of controlling refrigeration in a refrigerator having a food compartment and an ice compartment, said method comprising circulating air from the food compartment against the metallic face of the ice compartment to refrigerate said air, said circulation including diversion of said air through passages adjacent the metallic face of the ice compartment, and restricting said passages to control the flow of air therethrough and the degree of refrigeration produced.

10 15. In a refrigerator having a food compartment and an ice compartment, the ice compartment having a metallic face against which air from the food compartment may circulate for refrigeration, a drip pan placed below and spaced from said metallic face to cooperate therewith to provide an air circulation passage therebetween, the sides of the drip pan being spaced from the metallic face, and gate valves carried off said drip pan adjacent said spaces between the ends of the drip pan and the metallic face to control the circulation of air through said spaces.

20 25. In a refrigerator having a food compartment and an ice compartment substantially sealed against entry of air from said food compartment, the ice compartment having a metallic face against which air from the food compartment may circulate for refrigeration, a drip pan placed below and spaced from said metallic face to cooperate therewith to provide an air circulation passage therebetween, the sides of the drip pan being spaced from the metallic face, and gate valves mounted adjacent said spaces between the ends of the drip pan and the metallic face to control the circulation of air through said spaces.

30 35. In a refrigerator having a food compartment and an ice compartment provided with a metallic face against which air from the food compartment may circulate for refrigeration, a circulation control device positioned within the food compartment and including an element arranged to cooperate with said face to provide air passages converging to a common discharge outlet, said outlet extending substantially from one wall of the refrigerator to the opposite wall, and

means carried by said element for restricting the flow of air through said passages to control the degree of refrigeration produced.

40 45. In a refrigerator having a food compartment and an ice compartment provided with a metallic face against which air from the food compartment may circulate for refrigeration, a circulation control device positioned within the food compartment and including an element arranged to cooperate with said face to provide air passages converging to a common discharge outlet and to prevent dripping of condensate through said discharge outlet, and means for restricting the flow of air through said passages to control the degree of refrigeration produced.

50 55. In a refrigerator having a food compartment and an ice compartment provided with a metallic face against which air from the food compartment may circulate for refrigeration, a circulation control device positioned within the food compartment and including an element arranged to cooperate with said face to provide air passages converging to a common discharge outlet, said element including valve means arranged to restrict the flow of air through the said passages, the said outlet extending substantially from one wall of the refrigerator to the opposite wall.

60 65. In a refrigerator having a food compartment and an ice compartment, the ice compartment having a metallic face provided with heat conducting ribs against which air from the food compartment may circulate for refrigeration, a circulation control device positioned within the food compartment and including an element arranged to cooperate with said face and ribs to provide air passages converging to a common discharge outlet, the said outlet extending substantially from one wall of the refrigerator to the opposite wall, and means carried by said element for restricting the flow of air through said passages to control the degree of refrigeration produced.

70 75. In a refrigeration control device, a drip pan comprising side walls spaced apart by a floor member having an opening therein, and means carried by the said side walls and cooperating with the floor to provide air passages and valve means carried by said pan for regulating air flow through the said opening.

SAUL C. HOFFBERGER.
